CLOSED END MAGNETRON

Willis E. Lamb, Jr., New York, N. Y., assignor to
United States of America as represented by the
Secretary of War

Application April 9, 1946, Serial No. 660,604

7 Claims. (Cl. 315—40)

1

This invention pertains to a magnetron in which the cover plates are soldered directly to the ends of the anode, to thereby eliminate the usual end zone.

One of the objects of this invention is to provide a magnetron having very good mode separation.

Another object is to provide a magnetron having a low pulling figure.

Still another object is to provide a magnetron in which a high ratio of resonator lengths may be employed.

Still another object is to provide an arrangement whereby a magnetron may be converted to operate at shorter wavelengths than that for which originally designed.

These and other objects will become apparent in the specification and in the accompanying drawing in which:

Figure 1 shows the section through the closed end magnetron anode; and

Figure 2 shows a sectional view along line 2—2 of Fig. 1.

As shown in Figures 1 and 2, the magnetron anode is of the Rising Sun type and comprises the anode body 10 provided with the usual small and large cavities 11 and 12 respectively and with vanes 13 extending radially between the cavities toward the cathode. A pair of end plates 14 and 15 are soldered or otherwise attached directly to the ends of the anode body and are provided with openings 16 and 17, respectively, to permit passage of the cathode, not shown.

In the construction shown the usual end space has been completely eliminated. The same anode with open ends has no variation of the radio frequency field along its length and has a wave length of λ_0 for the π mode. This anode with its ends closed in accordance with this invention has a sinusoidal variation of the radio frequency field along the height of the anode with the result that the wave length λ is smaller. The new value of λ is given by the formula:

$$\frac{1}{\lambda^2} = \frac{1}{\lambda_0^2} + \frac{1}{4h^2} \quad (1)$$

where h is the height of the anode. Thus, the smaller the h the smaller is λ for a given λ_0 . As an example it may be assumed that it is desirable to have

$$\lambda = 1.25 \text{ cm.}$$

Thus it is clear that h may be determined as a function of the initial wave length λ_0 . Inasmuch as most low wavelength anodes of the type illustrated are produced by hobbing, it is desirable to maintain λ_0 relatively small in order to retain feasibility of hobbing. The result of this limitation is that h can not be as small as desirable on account of magnetic field considerations.

For example, if a value of h is chosen as 0.276",

a value for λ of 2.77 cm. would be necessary. As a compromise, in order to compensate for the effect described above $\lambda_0 = 1.60$ cm. was used in constructing the sample described below requiring a corresponding $h = 0.394"$.

A possible disadvantage of this construction may be considered to lie in the fact that the percentage of mode separation is decreased by the lowering of wavelengths produced by the presence of the end plates namely,

$$\frac{\delta\lambda}{\lambda} = \left(\frac{\lambda}{\lambda_0} \right)^2 \frac{\delta\lambda_0}{\lambda_0} \quad (2)$$

From the sample dimensions given above

$$\frac{\lambda}{\lambda_0} = 0.61$$

so that about 39% of the original mode separation from the $n=8$ mode is lost on account of the end plates. In many anode designs mode separation is at a premium and it would ordinarily follow that a closed end anode is not desirable.

However, I have found that with the Rising Sun design of magnetron shown in the drawing, field mode separation with closed ends may be obtained by simply using a high ratio R of resonator lengths. In the example cited, the 39% loss in mode separation can be compensated for by increasing R to a value of 2.0, from the expected value of 1.7, which, in the light of previous experience, would appear to be best in 18 vane open ended anodes.

A typical example for an 18 cavity Rising Sun magnetron has the following dimensions:

35	Anode diameter	$D_a = 0.170"$
	Cathode diameter	$D_c = 0.102"$
	Small resonator end diameter	$D_m = 0.324"$
	Anode height	$h = 0.394"$
	Large resonator end diameter	$D_M = 0.502"$

According to well known empirical formulae the λ_0 for this example would be 1.60 cm. and hence λ should have a value of 1.25 cm. Actually the constructed sample shows the π mode at 1.305 cm. with a low pulling figure of about 8 megacycles. Open ended anodes do not decrease in pulling with increase in height, therefore, this reduction is good, indicating that the transformer slot can be widened with considerable simplification of construction.

50

$$\text{The pulling figure} = \frac{5c}{12\lambda Q_{ext}}$$

Where c is the velocity of light and $Q_{ext} = 2\pi$ times the energy stored per cycle divided by the energy provided to the load per cycle. In an anode provided with closed ends and having approximate equality of anode height and transformer height only the central part of the anode is strongly coupled to the load due to the sinusoidal variation of the radio frequency field along the

height. The stored energies in the open end and closed end anodes may differ for equal operating conditions, for in the closed end anode the overall size is larger and the decrease in

$E_o + Hz$ (tangential circumferential component of electric field and axial component of the magnetic field)

near the end plates is compensated for by the radial component of H which is not present in open ended anodes.

Thus, the stored energy may be as high or higher in the closed end anode and the higher Q_{ext} and the smaller pulling are accordingly understandable. The presence of the anode ends in the manner shown results in a shorter wavelength. This arrangement may therefore also be used with existing anodes to increase the frequency of operation at the expense of slightly increased operating voltage. Thus my invention adds another variable to magnetron design, the use of closed ends permitting improvement in either the direction of increased mode separation or lowered wavelength as may be desirable or necessary in a particular application.

Efficiencies of approximately 30% are obtainable in the 1 cm. range of wavelengths with closed end anodes constructed according to the figures given in the above example. Although I have disclosed my invention in conjunction with the Rising Sun type of anode, closed ends may be employed with magnetron anodes having any number of cavities and having cavities of any configuration.

While I have shown a single embodiment of my invention it will be apparent to those skilled in the art that many modifications and applications are possible and I do not intend my invention to be limited except by the scope and spirit of the appended claims.

I claim:

1. A magnetron anode, comprising a cylindrical body, radially disposed and inwardly extending vanes in said body, said vanes extending along less than the whole radius of the body and forming alternate like and adjacent unlike cavity resonators therebetween, said resonators being open at the ends of said body, and an end plate at each end of the body directly secured to said ends and said vanes to close said resonators, said plates being formed with a central aperture circumferentially coincident with the inner ends of said vanes.

2. A magnetron anode having alternate like and adjacent unlike cavity resonators, said resonators extending the full length of said anode, and end plates attached directly to the ends of said anode to eliminate the end space between said resonators.

3. A magnetron anode provided with a plurality of vanes, said vanes forming a plurality of cavity resonators, alternate ones of said resonators having a like configuration, adjacent ones of said resonators having an unlike configuration, and end plates attached directly to each end of the body of said anode, said end plates completely closing the end spaces of said resonators, said end plates providing openings for the passage of a cathode.

4. A magnetron anode provided with a plurality of vanes, said vanes forming a plurality of cavity resonators, alternate ones of said resonators having a like configuration, adjacent ones of said resonators having an unlike configuration, and end plates attached directly to each end of the body of said anode, said end plates completely closing the end spaces of said resonators.

5. A magnetron anode having a plurality of cavity resonators, alternate ones of said resonators having a like configuration, adjacent ones of said resonators having an unlike configuration, and end plates attached directly to the ends of the anode to thereby avoid communication between said resonators at their ends.

6. A magnetron anode comprising an anode body having a plurality of cavity resonators therein, alternate ones of said resonators having a like configuration, adjacent ones of said resonators having an unlike configuration, said resonators being open at each end of said anode body, and end plates connected to the ends of said anode body to close the end spaces of said resonators at both ends of said anode body.

7. A magnetron anode comprising an anode body having a plurality of cavity resonators and two ends, alternate ones of said resonators having a like configuration, adjacent ones of said resonators having an unlike configuration, said resonators being open at said ends, and end plates directly soldered to said ends to eliminate the end spaces of said cavity resonators.
